[57] CLAIM

The ornamental design for a decorative plastic panel
for a door surface, substantially as shown and de-
scribed.

DESCRIPTION

FIG. 1 is an isometric view of the plastic panel embody-
ing the decorative design of my invention;

FIG. 2 is a side elevational view as seen from either the
right or left of FIG. 1;

FIG. 3 is a side elevational view as seen from either the
top or bottom of FIG. 1; and

FIG. 4 is a cross-sectional view along the lines 1—1 of
FIG. 1.

FIG. 1

FIG. 2

FIG. 3

FIG. 4
